UNITED STATES PATENT OFFICE.

MILTON MEYER, OF NEWARK, NEW JERSEY.

DISINFECTING DEVICE.

Application filed February 28, 1920. Serial No. 361,989.

To all whom it may concern:

Be it known that I, MILTON MEYER, a citizen of the United States, residing at Newark, in the county of Essex and State of New Jersey, have invented a new and useful Disinfecting Device, of which the following is a specification.

My invention relates to a disinfecting device particularly adapted to be used in connection with water closet bowls.

Attempts have heretofore been made to provide a disinfectant container which could be fitted to the recess beneath the inwardly extending hollow rim formed around the upper margin of the ordinary water closet bowl, in position to charge with a suitable disinfectant the streams of water flowing from the hollow rim to flush the bowl. These containers have consisted of resilient, perforated tubular members which were adapted to be sprung into place in the recess and to take a horseshoe-shaped formation following the forward and lateral curved portions of the bowl. Disinfectant containers of this general type, while filling satisfactorily the hygienic and sanitary requirements which they are designed to meet, have been open to the serious objection that it has been found difficult or impossible to keep the forward portions of the device in place in the forward part of the recess. This has been due to the fact that the exertion of outward pressure by the resilient tubular member had its greatest effect at the oppositely disposed extreme end portions of the tube, this pressure causing the end portions to press outwardly against the sides of the bowl and to act in a certain sense as pivot points about which the entire forward portion of the curved tube had a tendency to swing downwardly under the action of water pouring on the upper surface thereof. While the pressure of the ends of the tube against the side of the bowl was substantial, there was no corresponding degree of pressure constantly exerted by the forward portion of the curve against the forward portion of the bowl, since there was no factor except friction to prevent the sides of the tube from sliding rearwardly along the sides of the recess to relieve any pressure that might be exerted in a forward direction by the forward bend of the tube. In addition, the outward pressure of the extreme ends of the tube apparently had the effect of diminishing the outward pressure exerted

by the remaining portions of the tube, thereby increasing the tendency of the forward curved portion of the tube to swing downwardly in the manner described.

It is the object of my invention to provide a disinfecting device of this general type which will be free from the objections referred to.

With this and other objects in view, I have ascertained that I can cause a substantial forward pressure to be constantly exerted by the forward bend in the container and thereby cause it to retain its operative position in the rim recess by providing each end of the container with a relatively rigid extension arm or strut member having a length such that when the device is placed in operative position in the recess, the rigid strut member will engage the rear framework of the bowl and thus hold the forward portion of the device pressed tightly against its seat in the forward portion of the recess. Another feature of the invention consists in the provision of a laterally offset relation between each strut member and the corresponding end of the tube, which serves to hold the extreme ends of the tube out of contact with the sides of the bowl and correspondingly increase the pressure exerted by the remaining portions of the tube and the rim recess. Still another feature of the invention resides in forming the container tube of a helically coiled wire or other member of a resilient nature and which may be of itself impervious to the action of water or other substances, or which may be coated with any desired impervious material.

In the drawing,

Figure 1 is a plan view of a bowl partly broken away to show the location of a disinfectant container embodying the invention.

Figure 2 is a view in side elevation of the container shown in Figure 1.

Figure 3 is a view in side elevation of a modified form of container equipped with laterally extending lugs.

Referring to the drawings, an elongated tubular member 10 is shown in Figure 2 which is adapted to be fitted into place in the recess 11 formed beneath the shoulder provided by the inwardly projecting rim 12 of the bowl 13 shown in Figure 1. The tubular member or container 10 preferably consists of a coil of wire or other resilient material having a helical or other open formation

2
 which provides for the access of water flowing from the hollow rim to any suitable disinfecting material 14 contained within the tube. In order to hold the coil pressed forwardly into close contact with the forward part of the bowl, an extension arm or strut member 15 is provided which in the drawing is shown as being integral with and a continuation of the wire member of which the coil is formed, but which may be separately formed and attached to the ends of the tube. The strut members 15 are preferably of such length that a slight compression of the coil longitudinally along the sides of the horseshoe-shaped curve is produced in order to bring the ends of the struts into abutting engagement with any suitable surfaces 16 forming part of the rear portion of the bowl, to thereby force the forward curved part of the tube into firm contact with the forward part 17 of the bowl.

In order to hold the end portions 18 of the tube out of lateral contact with the sides of the bowl and thereby bring about a close contact 25 of the remaining portions of the curved tube with the sides of the bowl, the strut members 15 are preferably offset as at 19 at the points where they join the ends of the tube. It will be seen that this construction has the effect of 30 holding the adjacent tube ends out of contact with the bowl as at 20 so that the tendency present in tubes not so equipped to closely engage the bowl only at the extreme ends of the tube and to swing downwardly about the 35 ends as pivotal points, is overcome.

While I have shown the coil forming the tube as made up of flat wire, I wish it understood that round wire, or wire of any other cross-section may also be used, and also that 40 other material than wire may be employed it being desirable merely to use material that has sufficient resiliency to spring outwardly into contact with the surrounding bowl wall. When formed of metal the tubular member 45 is preferably coated with any suitable enamel or other material impervious to water or other substances. I have also shown the tube as round in section but this feature also can be modified and any conformation employed 50 that will fit the recess in which the tube is adapted to lie. Suitable plug members 21 may be employed to close the ends of the tube.

It will be seen that I have provided a device that is particularly well adapted for the purpose in view in that it can be easily placed in position where it will press closely against its seat and remain in place until removed by the caretaker.

60 While I have referred to the strut members as being rigid in character, this rigidity

is to be understood to exist relatively to the non-rigid or compressible character of the tubular container. In certain cases I may omit the rearwardly extending thrust members and rely for the desired results on laterally extending lugs 22 or other members or attachments carried by the ends of the tube for the purpose of holding the tube ends out of contact with the sides of the bowl for 70 the purpose referred to.

What I claim is:

1. A container for disinfectants comprising: an elongated resilient and longitudinally compressible tubular member having openings in its walls, and rigid extension members carried by the ends of said tubular member, said extension members being laterally offset from the ends of the tubular member.

2. A container for disinfectants comprising: a resilient tubular member formed of a helically coiled member, said tubular member being formed to fit in the recess beneath the inwardly directed rim of a bowl and to contain disinfecting material, the ends of the tube being provided with strut members arranged to be placed against a rear portion of the bowl to thereby hold the coiled member under longitudinal compression with the forward portion thereof held in close engagement with the forward portion of the bowl, and said strut members being laterally and outwardly offset with relation to the ends of the tube to hold the said ends out of engagement with the sides of the bowl.

3. A container for disinfectants comprising: a resilient tubular member formed to lie within the recess beneath the inwardly extending rim of a bowl to hold disinfecting material, and means carried by the ends of said tubular member to hold said ends laterally out of contact with the sides of the bowl, whereby remaining portions of said tubular member are held in engagement with said bowl.

4. A container for disinfectants for closet bowls consisting of an elongated tubular member having openings in its side walls and arranged to extend parallel to and lie underneath the rim of the bowl, and means for holding a portion of the tubular member out of contact with the bowl.

5. A container for disinfectants for closet bowls consisting of an elongated tubular member having openings in its side walls and arranged to extend parallel to and lie underneath the rim of the bowl, and offset portions on said container for holding the end portions of the container out of contact with the bowl.

MILTON MEYER.
